Needham, MA (US)

U.S. Office Action dated Oct. 9, 2019, received in Design U.S. Appl.
No. 29/695,664, 6 pages.

(**) Term: **15 Years**

Primary Examiner — Michael A. Pratt

(21) Appl. No.: **29/743,206**

(74) Attorney, Agent, or Firm — Grossman, Tucker,
Perreault & Pfleger, PLLC

(22) Filed: **Jul. 20, 2020**

CLAIM

(63) Continuation of application No. 29/695,664, filed on
Jun. 20, 2019, now Pat. No. 891,015, which is a
continuation of application No. 29/611,782, filed on
Jul. 25, 2017, now abandoned.

We claim the ornamental design for a vacuum cleaner and a
detachable canister for a vacuum cleaner, as shown and
described.

FIG. 1 is a perspective view of a vacuum cleaner including
a detachable canister, showing the new design;
FIG. 2 is a front view thereof;

FIG. 3 is a back view thereof;
FIG. 4 is a left side view thereof;
FIG. 5 is a right side view thereof;
FIG. 6 is a top view thereof;
FIG. 7 is a perspective view of a detachable canister for a
vacuum cleaner, showing another embodiment of the new
design;

FIG. 8 is a front view thereof;
FIG. 9 is a back view thereof;
FIG. 10 is a left side view thereof;
FIG. 11 is a right side view thereof;
FIG. 12 is a top view thereof; and,
FIG. 13 is a bottom view thereof.

(Continued)

The details shown in broken lines form no part of the claimed design.
